UNITED STATES PATENT OFFICE

2,158,746

HARROW

Joseph Dinwiddie, Caneyville, Ky.

Application April 28, 1938, Serial No. 204,874

1 Claim. (Cl. 55—73)

This invention appertains to new and useful improvements in agricultural machines and more particularly to a harrow.

The principal object of the present invention is to provide a harrow especially adapted for hill-side tilling.

Another important object of the invention is to provide a harrow constructed in such a manner that the parts can be easily reversed so as to avoid turning of the machine at the end of a field.

Still another important object of the invention is to provide a harrow of the character stated constructed in such a manner as to prevent "doubling over" in paralleling harrowed ground.

Other important objects and advantages of the invention will become apparent to the reader of the following specification.

In the drawings:—

Figure 1 represents a perspective view of the harrow.

Figure 2 is a top plan view with the beam in the act of being swung to reverse the parts for reverse travel of the machine.

Figure 3 is a top plan view of the machine with the draft beam reversed.

Referring to the drawings, wherein like numerals designate like parts, it can be seen that the machine consists of the annular frame 5 diametrically under the same passing the bar 6 which is provided with the upstanding lug 7 secured thereto. The bar 6 is provided with the depending intermediate portion 8 vertically bored to receive the headed pin 9 which passes downwardly through the draft beam 10 and through the rocker 11. The forward end of the draft beam 10 is provided with the mounting 13 for the vertical disk 14 while mounted upon the rear end of the beam 10 is the seat 15 secured to the beam by the spring 16.

The land side of the machine has the T-head formation 17 swingably connected to the bar 6 as at 6a each end of which is thickened and vertically bored to receive a shaft 18, the shafts being provided with laterally disposed arms 19 at their upper ends. The free ends of these arms are apertured to receive the pintle ends of the rods 20—20, these rods 20—20 having their inner ends bent downwardly into openings of the ends 50 of the rocker 11.

The lower ends of the shafts 18 are bent inwardly to form stub shafts 21 for the stay wheels 22.

A brace bar 23 extends between each end of 55 the T-head frame 17 and the annular frame 5

consisting of turnbuckle connected sections, the outer end of each outer section being pivotally connected to the T-head formation 17 as at 23a.

The other end of the bar 6 is provided with the connection formation 24, the lower end of which is secured to the shaft which extends transversely under the machine and carries the ground engaging disks 25.

A vertically disposed shaft 26 extends upwardly through the portion 24 and across the opening 10 therein, the lower end of this shaft 26 being provided with the inclined stub axle 27 on which the toed stay wheel 28 is mounted.

An arcuate shaped cross bar 29 is provided on the upper portion of the shaft 26 and a pair of crossed rod members 30 extend from the ends of the cross bars 29 to connect to the end portions of the rocker 11.

Brace members 31 extend from the formation 24 to connect to the annular frame 5.

As shown in Figure 1, the pin extends downwardly through the beam 10 and through the rocker 11, at each side of which is a washer 11a. The brace 5a has its ends connected to the annulus 5 and the pin 9 extends downwardly through 25 the brace 5a and into the upper portion of the box 25a through which the shaft carrying the disks 25 passes. Brace members 25b extend upwardly from ears on the box 25a to the brace 5a.

It will be observed, that the machine will afford 30 a smooth tillage from the foot of a hill to the top thereof and that there will be no lost energy as in "double disking" when a considerable amount of the draft energy is lost.

The stay wheels are preferably mounted in 35 roller bearings. Furthermore, when the machine has travelled to one end of the field, the stay wheels will hold the frame against turning as the team is swung around and the beam 10 is rotated on the frame 5. In this connection, it can be seen that the guide 32 prevents the beam from lifting from the frame 5, while the reduced portion 33 of the beam is so constructed as to avoid the connecting rod.

It will be observed, that the stay wheels will 45 run in the disk furrow and will prevent the machine from rocking when the beam or tractor has the pull directly on the center of the machine. Obviously, when the beam 10 is rotated on the frame 5 the position of the beam will 50 be reversed as shown in Figure 1. Obviously as the bar 11 is moved, the connecting rods 20 acting on the arms 19 will change the position of the wheels 22—22 and simultaneously the wheel 28 will be acted upon by reason of 55

the connecting rod connections 38 between the arm 11 and the arcuate cross-member 29. This will set the stay wheels in the proper angular relation for operation of the harrow in reverse direction, thus eliminating the turning of the entire implement.

While the foregoing specification has set forth the invention in specific terms, it is to be understood that numerous changes in the shape, size and materials may be resorted to without departing from the spirit and scope of the invention as claimed hereinafter.

Having described the invention, what is claimed as new is—

A harrow comprising a frame, a cross bar secured to the frame, a draft beam rotatably mounted on the frame, stay wheels at the end of the bar, means operated by rotation of the beam on the frame changing the position of the said stay wheels, said means consisting of a rocker, mounts for the stay wheels, and connections between the rocker and the stay wheels for resetting the stay wheels when the draft beam is rotated on the frame to permit the machine to be pulled in an opposite direction. 5 10

JOSEPH DINWIDDIE.
